BEVERAGE DISPENSER HEAD OR SIMILAR ARTICLE

Richard T. Cornelius, Minneapolis, Minn., assignor to The Cornelius Company, Anoka, Minn., a corporation of Minnesota

Filed Dec. 30, 1963, Ser. No. 77,971

Term of patent 14 years

(Cl. D2—3)

FIG. 1 is a front perspective view of a beverage dispenser head showing my new design.

FIG. 2 is a rear perspective view thereof.

FIG. 3 is a rear elevational view thereof.

The post members of the dispenser head are shaded to indicate a contrast in colors.

The dominant features of my design reside in the full line portions.

I claim:

The ornamental design for a beverage dispenser head or similar article, substantially as shown and described.
